AIR-INTRODUCING DEVICE

Karl Gustaf Eklund, Storangen, and John Evert
Hulten, Stockholm, SwedenApplication October 20, 1941, Serial No. 415,830
In Sweden December 2, 1940

3 Claims. (Cl. 98—40)

Our invention relates to ventilation systems and more particularly to devices for introducing air into rooms, in which curved or oblique deflecting surfaces are provided in a discharge opening to effect a proper distribution of the air in the room and to avoid draught.

One object of the invention is to provide a simple construction of an air introducing device which can be easily mounted in the opening of an air conduit.

Another object of our invention is to construct the air introducing device so as to enable various direction of the flow of air within wide limits by simple means.

A further object of our invention is to provide a valve device in combination with air distributing and directing means.

With the foregoing and other objects in view, as will appear as the description proceeds, our invention resides in the combination and arrangement of parts and details of constructions described herein and particularly pointed out in the appended claims, it being understood that changes in the particular embodiment of our invention may be made within the scope of what is claimed without departing from the spirit of the invention. We intend no limitations other than those of the claims when fairly interpreted in the light of the full disclosure and the state of the art.

In the drawing:

Fig. 1 is a front elevation of the air introducing device according to one embodiment;

Fig. 2 is a central section on line A—A in Fig. 1,

Fig. 3 is a rear elevation of the device according to a second embodiment,

Fig. 4 is a central axial section of the device illustrated in Fig. 3, and

Fig. 5 is a front elevation of the same device.

In the drawing 1 designates an adjustable body provided with a central bore which forms the air discharge opening or passage of the device. At the outer periphery thereof said body is formed with spherical guide surfaces, and the body is supported on said surfaces, by means to be described hereinbelow, in such a manner that the longitudinal axis of the air passage may be set in any direction within a certain maximum angle. In the air passage the body 1 carries a number (four in the drawing) of helical vanes 2 having well rounded end edges 3. These vanes cause the air passing the discharge opening to rotate and when leaving the opening to be thrown out in a spiral motion the velocity of which decreases in proportion to the distance from the opening of the device. A rapid mixture of the admitted air

with the air already present in the room will be obtained thereby.

Although we prefer helical vanes a similar distribution effect may be obtained by forming the vanes as plane plates set at an angle to the longitudinal axis of the discharge opening. Our invention is not limited to helical or plane oblique vanes in a passage having constant diameter but, alternatively, may be of any spiral or combined spiral and helical form in a passage the width of

which increases in the direction of flow.

To enable the adjustment of the spherical body with a view to discharge the air in various directions the body 1 is suspended between a frame 4 adapted to be attached to an air conduit in any suitable manner and an outer annular flange 4' by yielding means such as three blade springs 5 which are attached and secured by screws 6 and engage the spherical surface of the body 1. The annular flange 4' has an inner diameter which is smaller than the diameter of the spherical surface, and the springs 5 press the spherical body towards the outer flange 4' so as to provide for tightening engagement between the spherical surface and the edge 4" of the opening of the outer flange 4'.

A particular advantage of the illustrated construction resides in the fact that the attaching frame 4 is the only element of the device which need be mounted in the building in question during the work, i. e. when the walls, the ceiling, etc. are being made, whereas the more fragile parts of the device may be mounted afterwards and thus are exposed to injury during the construction of the building. After the remainder of the building has been completed, the valve body and the outer flange may be mounted. The three blade springs are applied simultaneously and are clamped between the flange and the frame for example by screws 6. The spring pressure actuating the spherical body causes this body to be maintained in place in its adjusted position and simultaneously the springs allow adjustment of the body so as to enable introduction of the air in any direction within certain limits.

The deflecting vanes may have their ends secured to transverse wires which may cross each other such as the wires 7 illustrated, and said wires may be clamped removably in the opening 50 of the body 1. In this or other manner the guide vanes may be kept together to form a unit which may be easily removed in case of desiring a concentrated air flow towards a certain place such as a work bench, a table or the like during particularly warm summer days. The invention

also includes an embodiment in which the ends of the passage in the body 1 may have provided therein helical notches for the ends of the wires so as to enable adjustment of the pitch or rise of the vanes by screwing the wires in or out at the outlet mouth of the passage or vice versa so as to decrease or increase the distance between the vanes. The distribution of the admitted air may be controlled by this means, and it is to be noted that in such arrangement the ends of the vanes may be pivoted on the wires.

In the embodiment illustrated in Figs. 3, 4 and 5, the device comprises valve means for control of the quantity of air admitted. Said valve means consists of two disks 10, 11 which together are able to cover the area of the passage and have, for example, a semicircular periphery and a straight-lined central edge, the latter being formed with a cylindrical lug 12, 13 by which the disks are pivoted on a pin 14 mounted diametrically in the inner mouth of the passage of the body 1. Mounted on the pin 14 and compressed between the opposite edges of the lugs 12, 13 is a helical spring 15 which tends to force the disks 10, 11 axially on the pin in opposite directions to engage each of two friction washers 16 and 17, respectively, secured to the body. One end of the spring thread engages one disk, and the other end thereof engages the other disk as shown in Fig. 3, and the spring may thus apply a shutting force to the disks if desired.

The disks 10, 11 may be set in the desired position on the pin by a hook 18 or any other suitable operating means. On setting the disk or disks to the position corresponding to the air admission desired the disk maintains the position to which it has been set, due to the friction afforded by the friction washer.

As shown in Fig. 4 the vanes 2 extend only a part of the length of the air passage in the lat-

ter embodiment leaving the other part thereof free to the disks 10, 11 which may be set in a position substantially in the longitudinal axial plane of the passage (Fig. 4). In the fully open position the valve means offers very little resistance to the air flowing through the device.

What we claim is:

1. An air introducing device comprising an air directing body having an air passage therein and a spherical peripheral surface, air deflecting vanes in said passage for rotation of the air flowing therethrough, an annular flange surrounding the body and having smaller inner diameter than the outer diameter of said spherical surface, and springs carried by said flange and engaging the spherical surface of the body to allow adjustment thereof and to force the body towards the flange to effect tightening engagement between the spherical surface and the flange.

2. An air introducing device comprising in combination with a frame for attachment to the mouth of an air conduit, an adjustable body mounted in said frame and having a bore forming an air passage therein, springs attached to the frame and holding said body removably in said frame by engaging the periphery thereof frictionally so as to allow adjustment of the body to direct the air in various directions.

3. An air introducing device comprising a body having an air passage therein, air deflecting vanes wholly within one part of said passage for rotation of the air flowing therethrough, valve means wholly within another part of the passage for the control of the air quantity admitted, a supporting structure and yieldable friction means carried by said structure to hold the body adjustably therein so as to allow air to be discharged in various directions.
